CLAIM

The ornamental design for a media backup device, as shown and described.

DESCRIPTION

FIG. 1 is an isometric view of a media backup device, in accordance with the design;

FIG. 2 is top view of a media backup device of FIG. 1;
FIG. 3 is a bottom view of the media backup device of FIG. 1;

FIG. 4 is a front view of the media backup device of FIG. 1;

FIG. 5 is a rear view of the media backup device of FIG. 1;
FIG. 6 is a left-side view of the media backup device of FIG. 1; and,

FIG. 7 is a right-side view of the media backup device of FIG. 1.

The evenly dashed broken lines in the figures depict portions of the media backup device that form no part of the claimed design.

1 Claim, 5 Drawing Sheets
